UNITED STATES PATENT OFFICE.

HENRY F. JONES, OF RANSOM, ILLINOIS.

CULTIVATOR AND PULVERIZER.

SPECIFICATION forming part of Letters Patent No. 351,934, dated November 2, 1886.

Application filed August 5, 1886. Serial No. 210,118. (No model.)

To all whom it may concern:

Be it known that I, HENRY F. JONES, a citizen of the United States of America, residing at Ransom, in the county of La Salle and State of Illinois, have invented certain new and useful Improvements in Cultivators and Pulverizers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in wheel-cultivators, the object of my invention being to provide a cultivator the axle of which can be adjusted laterally, said axle having attached thereto bars 20 which carry the cultivating-teeth, said bars being also adjusted laterally; and to this end my invention consists in the construction and combination of the parts, as will be hereinafter fully set forth, and specifically pointed out in 25 the claims.

In the accompanying drawings, which illustrate my invention, Figure 1 is a bottom view of a cultivator constructed in accordance with my invention. Fig. 2 is a plan view. Fig. 3 30 is an end view looking toward the rear of the cultivator; and Fig. 4 is a central section.

A refers to the central portion of the axle, the ends of which are recessed, as shown at *a*, the portions which extend above said recess 35 being provided with bolts *b b*, which pass through perforations therein. The axle A has attached thereto, by means of the bolts referred to, stub-axles A', which have extended portions *a'*, with a series of perforations through 40 which the bolts *b* pass, for holding said stub-axles to the center beam, and said stub-axles may be adjusted on the center beam laterally by placing the bolts in the different perforations formed therein. To the outer end of the 45 stub-axles A A' are attached supporting-wheels B B.

B' refers to a forwardly-extending draft-tongue, which is secured to the center portion of the axle A at its end and by means of 50 brace-rods *c c*. To the rear upper portion is attached, in the usual manner, a seat, D. The

center portion of the axle A is provided near the driver's seat with a rack-bar, E, with which the movable catch-rod of the lever F will engage. To the upper edge of the center portion of the axle A is also secured eyes or bearings *ff*, through which pass a crank-bar, G, the ends of which are bent forwardly or at right angles with the body portion of said bar. The lever F is also secured rigidly to said bar 60 in such a position thereon that the catch thereof will engage with the rack-bar E.

H H refer to the beams of the cultivator-frame, which are attached to each other at their front portions by a clevis, H', which has 65 the upper and lower rear portion spread and perforated for the reception of bolts *h*, which pass through the front portion of the cultivator-beams, and upon which said beams may be moved pivotally. To the under side of the 70 beams H are secured the cultivator teeth or shovels I, said cultivating-shovels being curved or spirally twisted at their lower ends, as shown. The upper portion of the cultivating-teeth have horizontal plates attached there- 75 to, which are slotted, as shown at *i*, through which pass bolts which extend through perforations in the beams. By thus slotting the plates, by means of which the cultivator-blades are attached to the frame, said blades 80 can be adjusted at different angles, as may be desired, and they may also be readily attached and detached from the beams.

The upper portion of the beams H H, at about their centers, are provided with transverse bars K, which are adjustable laterally upon each other, so as to hold the beams H in position. The inner ends of these bars K have perforations and securing-bolts. Immediately above the outer ends of the bars K are attached 85 angle-plates *k*, with perforations through which pass a bolt for securing in place a rearwardly-extending bar, K', which is pivotally attached to a bar, *l*, the ends of which are secured in the depending bars L, attached to the under 90 side of the axle A. The bolt which extends through the angle-plate *k* also secures in position the bars M, the upper ends of which are provided with perforations through which pass bolts *m*, attached to the outwardly-bent 95 ends of the pivoted bar G, which carries the lever F.

By the construction hereinbefore described it will be readily seen that by moving the lever F toward the draft-tongue, the bars which carry the cultivating-frame will be depressed so as to enter the soil to a greater or less extent, and when the same is moved rearwardly the cultivator-frames will be held above the ground. When the cultivator-frames are contracted so that their ends will be closer together, the bars K' will slide upon the transverse bar l. By means of the device hereinbefore described the axles of the cultivator may be contracted so that they may be quite close together, and the angles of the bars H H may also be changed, so that the track of the cultivator-blades will be very near each other. If desired, the front cultivators, or those nearest the forward beams, H H, may be removed, and the device may then be used as a straddle-row cultivator.

I am aware that prior to my invention it was not broadly new to attach cultivator-blades to a vertically-adjustable bar, so that the blades would enter the ground when said bar was depressed; and also that it is not new to curve the ends of the cultivator-teeth, and I do not, therefore, claim such construction, broadly; but

What I claim as new is—

1. The combination, in a cultivator, of a laterally-adjustable axle carrying supporting-wheels H H, having cultivators attached to the under sides thereof, said bars being con-

nected to each other at their forward ends by a clevis, bars J J, attached to the beams H, so that they can be adjustable one upon the other, and elevating and depressing means consisting of a crank-bar mounted on the axle, depending bars M, and rearwardly-extending bar K', which is adapted to slide upon a bar, l, which is secured to the axle by the depending bars L, the parts being combined and organized substantially as shown, and for the purpose set forth.

2. In a cultivator, the beams H, connected to each other at their forward ends by a clevis, H', through which passes bolts h h, for pivotally connecting the said pieces of frame to each other, bars K K, attached to the upper sides of the beams H, so that said bars can be adjusted upon each other, so as to expand or contract the rear ends of the beams, bars M and K, pivotally attached to the beams, the bars M being connected to a crank-bar having a lever; F, while the rearwardly-extending bar K' is pivotally attached to a bar, L, attached under the center portion of the axle, in combination with the laterally-adjustable axle having supporting-wheels, substantially as shown, and for the purpose set forth.

In testimony whereof I affix my signature in presence of two witnesses.

HENRY F. JONES.
